ROBERT N. ALLEN, OF METHUEN, MASSACHUSETTS, ASSIGNOR TO U. S. BOBBIN & SHUTTLE COMPANY, OF PROVIDENCE, RHODE ISLAND, A CORPORATION OF NEW JERSEY.

SELF-THREADING SHUTTLE.

1,145,649.

Specification of Letters Patent.

Patented July 6, 1915.

Application filed November 6, 1914. Serial No. 870,588.

To all whom it may concern:

Be it known that I, ROBERT N. ALLEN, a citizen of the United States, residing at Methuen, in the county of Essex and State 5 of Massachusetts, have invented a new and useful Improvement in Self-Threading Shuttles, of which the following is a specification.

This invention relates to certain new and 10 useful improvements in self threading shuttles, and the primary object of the invention is to provide an improved device for the purpose indicated which is of simple and economical construction and which can be 15 easily and quickly incorporated in the shuttle.

Further, the invention aims to provide a 20 threading device which will effectively prevent accidental unthreading during the shuttle movements.

In the drawings Figure 1 is a fragmentary top plan view of a shuttle having the present invention applied thereto; Fig. 2 is a section taken on the line 2—2 of Fig. 1. 25 Fig. 3 is a section taken on the line 3—3 of Fig. 2, and Fig. 4 is a detail bottom plan view of the threading device.

In proceeding in accordance with the present invention, the shuttle S is provided 30 with an inclined longitudinal bore or passage P which leads from the bobbin cavity or chamber through the front end of the shuttle so as to enable the threading device now to be described to be easily and quickly 35 driven into the bore.

The threading device is of substantially cylindrical form and is of hollow formation so as to provide a thread passage completely therethrough. A slot 1 is cut in one end of 40 the cylinder while a second similar slot 2 is cut in the opposite end of the cylinder, the slots 1 and 2 having a downwardly divergent relationship as shown in Fig. 2, and extending through the respective rear and 45 front ends of the cylinder and into a cutaway central portion 3 which is common to the inner ends of each of the slots. The front end of the threading device is cutaway at 4 and formed with a guard finger 5 which extends into a thread receiving 50 opening 6, which latter is located in the bottom of the cylinder, while the slots 1 and 2 are located in one of the sides of the cylinder. The cylinder is further provided with 55 a transverse opening 5' through which the

securing bolt 6' passes to hold the cylinder in position with relation to the shuttle.

The thread receiving opening 6 registers with the delivery eye passage D of the shuttle, the eye being provided with wear pins 8 on its opposite sides as depicted in Fig. 3, of the drawings. The cut-away part 4 provides a curved thread riding edge 9 on which the thread rides in entering the opening 6 and is prevented from being accidentally disengaged from the opening 6 by means of the guard finger 5.

In operation it will be understood, that there being slight space between the side of the cylinder opposite to the side which 60 lies adjacent to the delivery eye and the adjacent side of the passage P, as indicated at 10, the thread is placed longitudinally of the cylinder and drawn down through the space at 10, until the wall 11, which the cutaway 65 part 3 provides, is met with, whereupon the thread is drawn inwardly toward the interior of the cylinder which causes the thread to pass through the slots 1 and 2 and enter the cylinder interior. The thread 70 is then drawn to ride down the edge 9 and to pass the guard finger 5 which causes the thread to enter the opening 6, and passing 75 in the space 12 beneath the cylinder bottom enter the delivery eye. It will thus be apparent that accidental unthreading of the 80 shuttle is prevented, since to unthread same the thread must enter each of the slots 1 and 2, and due to the upwardly convergent 85 relationship of the slots, the chance of the 90 thread entering same or passing through same is reduced to a minimum, especially 95 since the wall 11 has an inclined disposition due to the inclination of the cylinder.

Having thus described my invention, I 95 claim as new and desire to secure by Letters Patent;

1. In a shuttle having an upwardly inclined longitudinal bore which leads from the bobbin cavity through the front end of the shuttle, a hollow cylindrical element having a central cutaway part in its top and a pair of upwardly convergent slots in its inner side which slots extend from the cutaway portion through the respective cylinder ends, said cylinder having a thread opening in its bottom and having its front end formed with a cutaway part which provides an inclined edge leading down and toward the opening, a guard finger extending 100 105 110

- into the opening and located at the termination of the inclined edge, there being space between the bottom of the cylinder at the front thereof and the adjacent part of the shuttle to enable the thread after riding down the inclined edge to pass the guard finger and then enter said thread opening and pass below the cylinder bottom and enter the shuttle delivery eye.
- 10 2. In a shuttle having an upwardly inclined longitudinal passage leading from the bobbin cavity through the front end of the shuttle, a hollow cylinder in said passage having a central cutaway part and a pair of slots leading from the cutaway part through the cylinder ends, said slots being divergently related and located on the inner side of the cylinder, the front end portion of the cylinder having an opening in its bottom
- 15 20 and a guard for the opening which latter is spaced from the adjacent portion of the cylinder to allow the thread to pass below the guard finger and to enter the opening.
3. In a shuttle having a bore, and a hollow cylinder in the bore having end slots which are located on one side of the cylinder and which are divergently related, and a central cutaway part interposed between and spacing the slots, the cutaway part providing a wall joining the slots and serving
- 25 to direct the thread thereinto, said cylinder having an opening in its bottom to receive the thread.
4. In a shuttle, a hollow cylinder the ends of which communicate with the delivery eye and the bobbin cavity, said cylinder having a central cutaway part and inclined slots leading therefrom through the ends of the cylinder.
5. In a shuttle, a hollow cylinder the ends of which communicate with the delivery eye and the bobbin cavity, said cylinder having a side entrance for the thread and having an opening in its bottom which is spaced upwardly from the bottom of the shuttle delivery eye to allow the thread to pass down through the opening into the delivery eye.
6. In a shuttle, a hollow cylinder the ends of which communicate with the delivery eye and the bobbin cavity, said cylinder having a side thread entrance and a bobbin delivery eye.

In testimony whereof I have signed my name to this specification in the presence of two subscribing witnesses.

ROBERT N. ALLEN.
